UNITED STATES PATENT OFFICE.

ERNEST V. PARKER, OF TACOMA, WASHINGTON.

VALVE-OPERATING FOR INTERNAL-COMBUSTION ENGINES.

1,317,310.

Specification of Letters Patent. Patented Sept. 30, 1919.

Application filed June 16, 1919. Serial No. 304,441.

To all whom it may concern:

Be it known that I, ERNEST V. PARKER, a citizen of the United States, and resident of the city of Tacoma, county of Pierce, 5 State of Washington, have invented certain new and useful Improvements in Valve-Operating for Internal-Combustion Engines, of which the following is a specification.

My invention relates to internal combustion engines, and means whereby the valve mechanism is operated, especially in such engines as employ air under pressure for starting. The type of engine to which this mechanism is particularly adapted is a type 10 which is ordinarily spoken of as Diesel or semi-Diesel.

The object of my invention is to provide a simple, reliable mechanism which may be controlled by the simple movement 15 of shifting a lever into various positions, and which, by so doing, will be caused to operate the valves after the manner required while running, or into such position as is required when starting under air, or to throw the 20 valve entirely out of action.

The features of this device which I deem to be new and upon which I desire to obtain 25 patent will be hereinafter described and then particularly defined by the claims.

30 In the accompanying drawings I have shown in a simple form of construction the manner of installing and operating my invention.

Figure 1 shows the cylinder of an engine 35 and the mechanisms employed in connection with my device for operating the valves thereof.

Fig. 2 shows a front elevation of the engine cylinder, together with the valve operating mechanisms.

Fig. 3 is a plan view of the valve operating mechanisms and their relations to the cylinders.

In engines of the type referred to it is 45 customary to employ air, which has been previously compressed and stored in a tank, as the means for starting the operation of the engine. When this is done the engine operates in the same manner as would an ordinary steam or compressed air engine. This 50 manner of operation is, of course, cut off as soon as the engine has been started and, in fact, the mechanisms necessary for the use

of air in starting may be applied to a portion only of the cylinders, where the engine 55 is one having several cylinders.

The particular construction of the engine cylinder and piston and of the valve thereof is immaterial to my present invention; I have, therefore, indicated these parts only 60 in a typical manner, the same being intended to represent any type of construction which may be employed for these parts. There would be employed a series of valves 1, the number depending, to a certain extent, upon 65 other features; the manner for actuating these, is also largely immaterial.

As herein shown, the valve is operated through the medium of a lever 10, which lever is pivoted in any suitable manner, as 70 upon a bracket 11, and this is operated through the intervention of a link or rod 2. The number of levers 10 and rods 2 employed, depend upon the number of valves 75 which are required for any particular cylinder. The mechanisms herein described can also be applied to as many cylinders as it may be desired.

The links or rods 2 are moved lengthwise 80 thereof under the normal action of operating the valves. They are independent of each other in their movement in this direction. They are, however, connected in such a manner that they must move together, so far as movement transversely of their length, this 85 being the movement which is given them in adjusting them for operation under different conditions, for instance, while running, while standing and while starting, for each 90 of these purposes they occupy a different position transversely of their length.

Each of these rods or links 2 has secured 95 to the end thereof a head 3, and this head has mounted thereon, either one or two cam rollers, the number varying with the different heads. In Fig. 2, wherein all of these links are shown side by side, I have indicated the individual links by the reference characters 20, 21, 22, and 23. The link 20 is the one which is used to control the exhaust valves. 100 The link 21 is the one which is used to control the fuel injection, 22 controls the starting air and 23 the air suction which provides the air charge for the engine cylinder.

If this device be applied to an engine of 105 the type wherein the charge is formed by

means of a carburetor, that is, wherein the fuel and the air are introduced together, then one of these valve operating mechanisms may be omitted, in which case the fuel injection and the air supply for the charge may be operated from the same link.

The heads 31, 32 and 33, being those which control respectively the fuel injection starting air and the air suction, or the supply for the charge, are each supplied with a single cam roller. These heads, as illustrated in Fig. 2, are differentiated for the different links by the reference characters 30, 31, 32 and 33. The heads, 31, 32 and 33 are alike in having a single cam roller 4, therein. The head 30, however, has a plurality of cam rollers located in different positions transversely of the length of the link 2. As herein shown they are provided with one roller 40 in the center of its width, and two rollers 41 located at each side of the center roller. The two rollers 41 are, however, to be considered as one, as they function alike.

All of the heads 3 are connected with a common operating mechanism for adjustment in the direction transversely of the length of the links 3. The means shown for adjusting this consist in connecting a link 5 to each head, which link extends substantially at right angles with the links 2, and connecting all of these links 5 with a rod 50 carried by a yoke 51 which yoke is secured to a shaft 52, which shaft is rocked by any convenient and suitable means, as for instance, by a crank arm 53, which crank arm may be extended so as to form a lever, or may be operated through a link 54, from any suitable position and by any suitable mechanism. The essential feature is that all of the heads 3 be moved laterally together; any suitable mechanism for securing this result may be employed.

All of the cam rollers carried by these heads, excepting that carried by the head which operates the starting air, and one set of those carried by the exhaust operating head, are located in alinement, these being the rollers which are shown at the right hand side of the head in Fig. 1. The roller which is carried by the head which operates the starting air, and one set, 41 of those carried by the exhaust operating head, are placed in alinement parallel with the other, but moved to one side thereof, these being the rollers which are shown at the left hand in Fig. 1 and which are differentiated by the reference character 41. These heads are shown by full lines in the position which they would occupy during the normal running operation of the engine. In dotted lines in Fig. 1 they are shown in the position which they would occupy when the engine was stopped. In an intermediate position, 65 being the position wherein the rollers 41

were alined with the center of the shaft 6, the parts are in position for starting the engine by the use of compressed air.

The shaft 6 is turned in any suitable manner from the engine shaft. For a four-cycle engine this shaft would turn at half the speed of the engine shaft. Upon this shaft are provided a series of cams for engagement with the rollers 4 and 41. Such of these rollers as are employed while the engine is running have a single lobe, as 60. Those cams which are employed while the engine is being started under air, are provided with two lobes placed oppositely, so that these valves are then operated twice as often as the valves which are employed while the engine is running. If, however, the engine is of the two-cycle type the number of lobes on all of the cams would be the same.

If the engine is one which must be reversed, some means must be provided whereby the cams will be operated under different timing for the reversal. The means which I have shown consists in providing the shaft 6 with a duplicate set of cams and then shifting the shaft, or at least a member mounted thereon to which the cams are secured, lengthwise of the shaft enough to position the two sets of cams for alternately engaging with the cam rollers.

As shown in Fig. 2, the cams which have been differentiated by the character 61 are employed for engagement with the cam roller 40, the cams 63 are employed for engaging with the cam roller connected by head 31, the cams 64 for engaging with the roller carried by the head 32 and cam 65 for engaging with the roller carried by the head 33.

If the shaft, or the member carrying these cams, be shifted to the right a distance corresponding with the separation of the corresponding cams of any set, these cams will alternate into position to engage with the cam rollers, and the valves will thus be operated in a manner for turning the engine in opposite directions. Any means desired and found suitable for shifting of this shaft may be employed.

The position of these parts shown by dotted lines in Fig. 1 is that occupied when the engine is stopped. In starting, the controlling lever is shifted so as to place the outer set of rollers, as 41, into position for engagement by the cams on shaft 6. This will operate only the air starting valves and the exhaust valves. When the engine is under way, the lever is shifted so as to place these heads in the last or final position which is shown by full lines in Fig. 1. In this position the air starting valves will not be operated. The exhaust valves will, however, be operated, as this head 30 has two sets of rollers 40 and 41. The air starting head, being the head 32, has but one roller,

but this is alined with the roller 41, and consequently, is not in position to be operated by the cams when the heads are in the normal running position.

- 5 5. What I claim as my invention is:
1. A valve operating gear for internal combustion engines comprising fuel injection, air supply, exhaust and starting air valves, a separate actuating head for each of
10 said valves, said heads being connected to be shifted together between neutral and operative positions, a rotative shaft having cams thereon for operating all of said heads, the exhaust, air suction and fuel supply
15 heads having cam rollers which are alined in the direction of the length of the shaft, and the air starting and exhaust heads having cam rollers offset to one side in the same direction from the other cam rollers.
- 20 2. A valve operating mechanism for internal combustion engines comprising fuel supply, exhaust and starting air heads carried by pivoted links to have a laterally swinging movement for adjustment between
25 working and neutral positions, said heads all being connected for adjustment together, a shaft having cams for actuating said heads the starting air and the exhaust heads having cam rollers alined in the direction of the
length of the shaft, and the fuel supply and 30 exhaust heads having cam rollers alined with the direction of the shaft and laterally offset from the other cam rollers.
3. A valve operating mechanism for internal combustion engines comprising starting air, fuel supply and exhaust heads, links connected each with its respective head, means for swinging said heads laterally of their operation movement for adjusting them between working and neutral positions, 35 a shaft having two sets of cams designed for reverse operation of the engine, means for shifting said cams lengthwise of the shaft to change from one set to the other, the exhaust head having two cam rollers offset in the 40 direction of the adjustment movement of said heads, the air starting head having a cam roller alined with one of the rollers on the exhaust head and the fuel supply head having a cam roller alined with the other 45 roller of the exhaust head, the cams engaging the air starting roller and alined roller of the exhaust head having twice the number of lobes as the cams which engage the other rollers. 50
